CLAIM

The ornamental design for a robot vacuum docking station and mat set, as shown and described.

DESCRIPTION

FIG. 1 is a front view of a robot vacuum docking station and mat set showing the claimed design;
FIG. 2 is a rear view of the robot vacuum docking station of FIG. 1;
FIG. 3 is a top view of the robot vacuum docking station of FIG. 1;
FIG. 4 is a bottom view of the robot vacuum docking station of FIG. 1;
FIG. 5 is a left view of the robot vacuum docking station of FIG. 1;
FIG. 6 is a right view of the robot vacuum docking station of FIG. 1;

FIG. 7 is a perspective front, top, right of the robot vacuum docking station of FIG. 1;

FIG. 8 is a perspective front, top, left of the robot vacuum docking station of FIG. 1;

FIG. 9 is a perspective rear, top, right of the robot vacuum docking station of FIG. 1;

FIG. 10 is a perspective rear, top, left of the robot vacuum docking station of FIG. 1;

FIG. 11 is a perspective front, bottom, right of the robot vacuum docking station of FIG. 1;

FIG. 12 is a perspective front, bottom, left of the robot vacuum docking station of FIG. 1;

FIG. 13 is a perspective rear, bottom, right of the robot vacuum docking station of FIG. 1; and

FIG. 14 is a perspective rear, bottom, left of the robot vacuum docking station of FIG. 1;

FIG. 15 is a front view of the mat of FIG. 1 without the robot docking station;

FIG. 16 is a rear view of the mat of FIG. 15;

FIG. 17 is a top view of the mat of FIG. 15;

FIG. 18 is a bottom view of the mat of FIG. 15;

FIG. 19 is a left view of the mat of FIG. 15;

FIG. 20 is a right view of the mat of FIG. 15;

FIG. 21 is a perspective front, top, right of the mat of FIG. 15;

FIG. 22 is a perspective front, top, left of the mat of FIG. 15;

FIG. 23 is a perspective rear, top, right of the mat of FIG. 15;

FIG. 24 is a perspective rear, top, left of the mat of FIG. 15;

FIG. 25 is a perspective front, bottom, right of the mat of FIG. 15;

FIG. 26 is a perspective front, bottom, left of the mat of FIG. 15;

FIG. 27 is a perspective rear, bottom, right of the mat of FIG. 15; and

FIG. 28 is a perspective rear, bottom, left of the mat of FIG. 15.

The broken lines in the drawings depict unclaimed subject matter that forms no part of the claimed design.
